UNITED STATES PATENT OFFICE

JESSE G. KING, OF DAYTON, OHIO, ASSIGNEE, BY MESNE ASSIGNMENTS, TO FRIGID-AIRE CORPORATION, A CORPORATION OF DELAWARE

LIQUID COOLER

Application filed February 21, 1927. Serial No. 169,745.

This invention relates to mechanically refrigerated liquid coolers, and more especially to devices for cooling drinking water.

One object of the present invention is to provide a self contained unitary structure enclosing a refrigerant cooling unit or evaporator which is in good thermal contact with a conduit or pipe coil through which water or other liquid may be circulated.

10 A further object of the invention is to provide a liquid cooling unit which is supported by a pedestal on the floor at a convenient height, the pedestal being constructed to house the refrigerant ducts connected with 5 the evaporator, a pipe connected with the liquid coil and other accessory pipes which may be used with the evaporator.

Further objects and advantages of the present invention will be apparent from the 20 following description, reference being had to the accompanying drawings, wherein a preferred embodiment of one form of the present invention is clearly shown.

In the drawings:

25 Fig. 1 is a vertical sectional view of one form of the invention. Fig. 1 also includes a diagram of refrigerating mechanism associated with the evaporator included in the cooling unit; and

30 Figs. 2 and 3 are sectional views taken respectively on the lines 2—2 and 3—3 of Fig. 1.

Referring to the drawings, 20 designates a case having thermally insulated walls 21 surrounded by a metal jacket 22. An end 35 wall 23 is removable to provide access to the interior of the case, and is secured in position by screws 24 passing through the metal jacket member 25, which is attached to the wall 23. The case 20 is supported by a pedestal 26, which is constructed so as to place the case 20 at a convenient height above the floor. The pedestal 26 is hollow in order to house certain pipes which are connected with the cooling unit within the case.

45 The case 20 houses a cylindrical boiler or

evaporator 30 containing refrigerant which is delivered to it through a pipe 31 and from which expanded refrigerant is withdrawn through a pipe 32. A float controlled valve 65, for instance of the type disclosed in the patent to R. G. Osborn, 1,556,708, patented October 13, 1925, controls the flow of liquid refrigerant into the boiler 30. The boiler 30 is surrounded by a pipe coil 33 formed of pipe of oblong cross section which may be wound on edge around the boiler 30, and which is thermally connected therewith in any suitable manner as by soldering. The narrower edges of the pipe coils are thus directly bonded to the boiler 30, and the broader sides of the coils are in contact with each other. In this way a large cooling surface is presented to the liquid flowing through the coil 33 and the metal path leading from the interior of the boiler to this cooling surface is sufficiently great to effectively transfer the heat.

One end of the coil 33 is connected with a pipe 34 leading from a source of liquid supply. In case the apparatus is used for cooling drinking water, the pipe 34 would be connected with the city water main. The other end of the coil 33 extends through one of the end walls of the case 20 and is connected exteriorly of the case with a faucet 35. Directly under the faucet the case is provided with a shelf 36 in the form of a shallow pan for supporting a drinking cup 37. The shelf 36 is connected with a drain pipe 38 extending through the case to the interior thereof and then through the bottom wall of the case through a hole 39. The boiler and coil 33 are supported, in any suitable manner, within the case 20 so that there will be a space between the coil 33 and the sides of the case. This space is completely filled with removable insulating material 40, such as kapok. The boiler 30 is provided with a removable end wall 41, to which the pipes 31 and 32 are connected by fittings 42 and 43 respective-

ly. After removing the end wall 23 and after detaching the pipes 31 and 32 from the fittings, these pipes may be bent away from the end wall 41 so that this part may be removed to provide access to the interior of the boiler 30 without removing the same from the case 20.

As shown in the drawings, pipes 31, 32 and 34 extend through an opening 44 in the bottom wall of the case 20 and downwardly with the pipe 38 through the hollow pedestal 26. The pipe 32 is connected with a refrigerant compressor pump 50, which is driven by an electric motor 51. The motor 51 also operates a fan 52 for cooling a condenser coil 53, having one end connected with the outlet of the compressor 50 and the other end connected with the pipe 31. In order to maintain the temperature of the pipe coil 33 within a predetermined range of temperature limits, the refrigerating apparatus is started and stopped automatically by means including an automatic switch 60, which controls the circuit of the motor 51 and which includes a flexible bellows 61 connected by a pipe 62 with a thermostat bulb 63 containing volatile liquid. As shown, the pipe 62 also extends upwardly through the pedestal 26.

It is apparent from the foregoing that the present invention provides a compact unitary structure which may be easily installed and connected with refrigerating apparatus and a source of liquid supply. The cooler may also readily be disassembled for repairs and adjustment.

While the form of embodiment of the present invention as herein disclosed, constitutes a preferred form, it is to be understood that other forms might be adopted, all coming within the scope of the claims which follow.

What is claimed is as follows:

1. A liquid cooler comprising, in combination, a cylindrical refrigerant chamber having walls of metal of good thermal conductivity, and a coil of flattened pipe of metal of good thermal conductivity wound on edge and having its turns metallically joined to the chamber and the flat sides of the turns of the coils abutting one another.

2. A liquid cooler comprising, in combination, a refrigerant chamber, a duct for receiving a liquid and in good thermal contact with the chamber, a liquid inlet pipe connected with the duct, refrigerant inlet and outlet pipes for connecting the chamber with refrigerating apparatus, a case having insulating walls for enclosing the duct and chamber, a hollow support for supporting the case and for enclosing said pipes, and liquid outlet extending exteriorly of the case and connected with the liquid duct.

3. A liquid cooler comprising, in combination, a case having insulating walls and an opening through the bottom thereof, a hollow base supporting the case, the interior of the

base communicating with the chamber through said opening, a refrigerant chamber within the case, a cooling coil surrounding the chamber and also located within the case, a liquid inlet pipe connected with the duct, refrigerant inlet and outlet pipes for connecting the chamber with refrigerating apparatus, said pipes extending through the hollow base and through said opening in the bottom of the case, and a faucet located on the outside of the case and connected through the case with the cooling coil.

4. A liquid cooler comprising a cylindrical refrigerant chamber, refrigerant control means within said chamber, a coil of pipe surrounding said chamber adapted to conduct the liquid to be cooled, the convolutions of said pipe being flattened and having their flat portions in contact with each other, said pipe being metallically attached to the exterior of said chamber.

5. In a liquid cooler, a unitary structure composed of a tank adapted to act as a heat exchange device, a coil of pipe surrounding the same exteriorly and adapted to conduct the liquid to be cooled, said pipe having flattened convolutions compacted together into intimate contact at their flat surfaces and being intimately metallically attached to said tank.

6. A liquid cooling device comprising a wall forming a refrigerant tank, automatic volatile refrigerant circulating means connected with an inlet and outlet in said tank, a float controlled valve for controlling the flow of unvolatilized refrigerant into said tank, walls forming a passage for liquid to be cooled, said last named walls being connected to the wall of said tank, said passage winding spirally around the refrigerant in said tank.

7. A liquid cooling device comprising a wall forming a horizontal refrigerant tank, automatic volatile refrigerant circulating means connected with an inlet and outlet in said tank, a float controlled valve for controlling the flow of unvolatilized refrigerant into said tank, walls forming a passage for liquid to be cooled, said last named walls being connected to the walls of said tank, said passage winding spirally about a horizontal axis around the refrigerant in said tank.

8. A liquid cooling device comprising a wall forming a refrigerant tank, automatic volatile refrigerant circulating means connected with an inlet and outlet in said tank, a float controlled valve for controlling the flow of unvolatilized refrigerant into said tank, walls forming a passage for liquid to be cooled, said last named walls being connected to the wall outside of said tank.

9. A liquid cooling device comprising a wall forming a horizontal refrigerant tank, automatic volatile refrigerant circulating means connected with an inlet and outlet in

said tank, a float controlled valve for controlling the flow of unvolatilized refrigerant into said tank, walls forming a passage for liquid to be cooled, said last named walls being connected to the wall outside of said tank, said passage winding spirally about a horizontal axis around the refrigerant in said tank.

5 In testimony whereof I hereto affix my signature.

CERTIFICATE OF CORRECTION.

Patent No. 1,750,893.

Granted March 18, 1930, to

JESSE G. KING.

It is hereby certified that error appears in the above numbered patent requiring correction as follows: Page 3, after line 8, insert the following as claim 10:

10. A liquid cooling device comprising a cylindrical wall forming a refrigerant reservoir, automatic volatile refrigerant circulating means connected with an inlet and outlet in said reservoir, a float controlled valve for controlling the flow of unvolatilized refrigerant into said reservoir, said automatic volatile refrigerant circulating means including an automatic refrigerant temperature control, a passage for liquid to be cooled, said named passage being in spiral form coaxial with and adjacent said cylindrical wall.

In the drawing, Figure 1, should appear as shown below instead of as shown in the drawing:

and that the said Letters Patent should be read with this correction therein that the same may conform to the record of the case in the Patent Office.

Signed and sealed this 29th day of May, A. D. 1930.

M. J. Moore,

Acting Commissioner of Patents.
